UNITED STATES PATENT OFFICE.

THOMAS M. MULKERINS, OF CHICAGO, ILLINOIS.

FAN.

No. 873,257.

Specification of Letters Patent.

Patented Dec. 10, 1907.

Application filed June 25, 1906. Serial No. 323,257.

To all whom it may concern:

Be it known that I, THOMAS M. MULKERINS, citizen of the United States, residing at Chicago, in the county of Cook and State of Illinois, have invented new and useful Improvements in Fans, of which the following is a specification.

This device relates to a fan driven by a spring motor, and among the principal features are means for operating the fan so as to be noiseless, whereby it may be used in places where silence is desirable, such as hospitals, bedrooms, confessionals, and the like. The fan is reversible so that it can be attached to the bottom or top of the driving shaft and is also provided with improved governing means which prevent the fan from running at too high a speed and at the same time avoids the vibrations and noise which usually accompany the running of an electric fan.

In the accompanying drawings, Figure 1 is a perspective view of the device, the casing being removed from same. Fig. 2 is a side view of the same showing it mounted on a bracket. Fig. 3 is a sectional elevation of the same. Fig. 4 is a plan of the ball bearing which supports the shaft of the governor. Fig. 5 is a section of a modified form of governor and Fig. 6 is an enlarged detail of the same. Fig. 7 is a section on the line 7—7 of Fig. 3.

The device has a frame with two plates 10 and 10^a, between which are mounted the gearing for driving the fan. 11 is a casing surrounding the same.

12 is a spring motor of any suitable or desired construction. By means of intermediate gearing, the motor drives a gear 7 which drives a pinion 8 on the main shaft 80 of the fan, which revolves the fan A and also the governor B. The shaft 80 is hollow and either end receives the stem or spindle 81 of the fan, which is fixed by a set screw 84 which engages the spindle. The fan is thus reversible with respect to the ends of the shaft and by reversing the direction of rotation of the shaft will make air currents in either direction out or in as desired. In using it for a downward current it is mainly to provide a circulation of the air in hot weather; in the other direction it is intended more for ventilation.

The governor has angular arms 24 pivoted to a sleeve 40 on the shaft 80, and the lower

ends or branches of the arms are provided with weights 24^b and the upper ends of the same have friction sleeves 24^c. These sleeves may be made of rubber, cork, leather, or the like.

25 is a cushioned plate mounted upon legs 25^a on the casing in position around the shaft to be engaged by the friction sleeves 24^c when thrown against the same by the centrifugal action of the weights. The cushion 25 is provided with a resilient packing, such as wadding, cotton, or the like.

In the modification shown in Figs. 5 and 6, for use when the device is arranged with the fan revolving on a horizontal axis, I employ a governing device consisting of several arms 28, mounted in sheaves 28^e, and each of these arms has a button 28^a mounted on a plunger 28^x behind which is a spring 28^c and a rod 28^d having a set screw 28^f for fixing the button at adjustment in or out. An annular cushion 29 is mounted upon the casing or frame, and the said buttons engage the inside of the same when revolving, creating friction which prevents too high speed.

The spindle 81 is movable or extensible in the hollow shaft 80. Thus the fan may be lowered or raised so as to bring the cooling breeze from the same nearer or farther away as desired. This is accomplished by adjusting the same by means of the set screws 84.

The weight of the fan and its appurtenances are carried entirely by one bearing, which consists of two concentric rings 90 and 91, extending around the shaft and having raceways 91^a and 91^b for the balls 92. These balls are spaced apart, and springs 93 are located there between to keep the same in position. The outer ring is supported by a hollow or annular bracket 94 attached to the base plate of the casing, the inner ring is fixed to the shaft.

100 is a set screw carried by a lug on the bracket, and it may be set against the shaft to stop the machine.

The rotation of the shaft 80 causes the weights 24^b to fly out according to the speed, and at a certain point this causes the arms to lift the sleeves against the under surface of the cushion 25, which produces friction and a noiseless braking action in consequence of the soft quality of the cushion. The reversal of the fan from one end of the shaft to the other allows it to be used in many places where it could not be other-

wise used, and a cheap and efficient fan is provided particularly suitable for use where freedom from noise is necessary or desirable.

I claim:

- 5 In a fan, in combination, a casing having upper and lower plates, a motor mounted thereon, a tubular fan shaft extending through the casing and mounted in bearings on said plates, gearing within the casing, 10 between the shaft and the motor, a spindle

adjustable lengthwise within the shaft, a fan, and means to attach the same to either end of the spindle.

In testimony whereof I have signed my name to this specification in the presence of 15 two subscribing witnesses.

THOMAS M. MULKERINS.
